UNITED STATES PATENT OFFICE.

DOROTHY D. MARSH, OF WASHINGTON, DISTRICT OF COLUMBIA.

GARMENT SUPPORTER.

Application filed July 28, 1923. Serial No. 654,338.

To all whom it may concern:

Be it known that I, DOROTHY D. MARSH, a citizen of the United States, residing at Washington, District of Columbia, have invented certain new and useful Improvements in Garment Supporters, of which the following is a specification.

This invention relates to certain new and useful improvements in garment supporters, 10 and more particularly to that class of them which is especially designed for supporting the diapers of infants.

One of the difficulties of providing any means for this purpose is the fact that the 15 skin of the infant is so extremely tender that only material of a very light character can be used, and that must be of a fine and soft quality. Another difficulty in a device of this character for infants is the fact that 20 the supporting bands which can be purchased in stores have too many points of contact to be supported. The infant walks, if he walks at all, only with difficulty, and if the support is too tight, it greatly impedes him and it is my desire to make a 25 supporting means such as not to catch or halt him in his movement, but one which will assist him in keeping his clothes from slipping down his legs and that without 30 any undue pressure upon the back or shoulders.

One of the objects I have in view, therefore, is to provide a device of simple construction, whose body belt is considerably 35 above the waistline so that it will not slip off the shoulders, but shows great efficiency in keeping its place notwithstanding the constant wriggling of the child. The devices shown in the stores are for older children, the body belt is much lower, and when 40 worn by an infant is found to be useless as it is constantly slipping off the shoulders. My apparatus overcomes this difficulty.

With these and other objects in view 45 which may be incident to my improvements, the invention consists in the parts and combinations to be hereinafter set forth and claimed, with the understanding that the several necessary elements comprising my 50 invention, may be varied in construction, proportions and arrangement without departing from the spirit and scope of the appended claim.

In order to make my invention more 55 clearly understood, I have shown in the accompanying drawings means for carrying

the same into practical effect, without limiting the improvements in their useful applications to the particular constructions, which for the purpose of explanation, have 60 been made the subject of illustration.

In the drawings:

Figure 1 is a perspective view of an infant wearing one of my improved supporters;

Fig. 2 is a like rear view of the device alone; and

Fig. 3 is an enlarged detail perspective of one of the supporting bands detached from the harness proper.

Like reference numerals represent the same or corresponding parts throughout the several views of the drawing.

The numeral 1 is a band made of tape 75 adapted to encircle the chest 2 of the infant and provided with shoulder bands 3 and 4, the ends of which are sewed thereto obliquely, as seen at 5 and 6, and 7 and 8 in Fig. 2, so as to fit over the shoulders of the child well up towards the neck rather than 80 over the shoulder proper, so as to avoid any interference with the free movement of the child's arms.

As seen in Fig. 2, the chest band 1 is provided with a button 10 and a buttonhole 11 85 upon the respective ends of the band which enables it to be easily and quickly adjusted around the body of the wearer.

Attention is invited to the fact that the band is not intended to encircle the waist, 90 but to be nearer the arm pits than the waistline both for ease and comfort of the child, and also to avoid as far as possible its becoming wet. It may be stated in this connection that because my chest band fits almost up to the arm pit, is the reason of its success, for it matters not how much the child wiggles, the harness stays in place.

Upon each side of the body band 1 and at the points 12 equi-distantly spaced between 100 the shoulder bands 3 and 4, are provided dependent supporting bands 13, the same consisting of a piece of tape or other suitable material doubled for wear and strength, and so as to fit over and depend 105 from the body band to which it is permanently stitched by a single or double row of stitches 14. The ends of each of these bands fit into a rectangular piece 16 of like material doubled upon itself and sewed at one 110 end 17 at the top and bottom 18 and 19, the piece as a whole having the appearance of

an inverted T. As seen in Fig. 3, the end piece 16 is provided with eyelets 21 and 22. These are provided to more readily enable the mother or nurse to attach the safety pins, the prong of each of which is inserted through one eyelet and then through the other and in this manner facilitates the changing of diapers.

The front portion of the band at a point 10 which is equi-distantly located between the shoulder bands is provided with a supporting band 13 like the side bands, except longer. Each of these rectangular pieces 16 is provided with a safety pin by means 15 of which it is fastened to the diaper.

It will be observed that the support bands 13 are equi-distantly spaced with respect to each other and that each support band is centrally located between the shoulder 20 bands, also that each of the side support bands 13 are sewed to the main encircling band at a point immediately under the arm pit. The object of this is to enable the mother to fasten the diaper at a point either 25 directly under that portion of the body or at a point slightly toward the rear thereof so that there will be no pressure against the stomach of the child and no pressure pulling on the shoulders by reason of the efforts

of the child to crawl or walk as soon as it 30 becomes sufficiently advanced to do so.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding 40 the scope of the appended claim.

I claim:

A garment support of the class described comprising a continuous encircling chest band, means whereby the ends of the band 45 may be secured together at the back, shoulder straps fastened obliquely to the chest band, support bands at each side and at the front depending from the chest band, the straps equi-distantly spaced with respect 50 to each other between the shoulder straps, the front support band being longer than the other two, end pieces attached to the straps and means for attaching the diaper of an infant to the end pieces. 55

In testimony whereof I affix my signature.

DOROTHY D. MARSH.
